UNITED STATES PATENT OFFICE.

ERIC E. HALL, OF CHICAGO, ILLINOIS.

FLOOR AND WALL CONSTRUCTION.

Application filed April 28, 1922, Serial No. 557,099. Renewed April 20, 1925.

To all whom it may concern:

Be it known that I, ERIC E. HALL, a citizen of the United States, and a resident of Chicago, in the county of Cook and State 5 of Illinois, have invented certain new and useful Improvements in Floor and Wall Construction, of which the following is a full, clear, and exact specification.

My invention is concerned with concrete 10 floor construction, and is designed to produce a novel and cheaply constructed border therefor, which can be used to secure carpets or other floor covering in place.

To illustrate my invention, I annex here- 15 to a sheet of drawings, in which the same reference characters are used to designate identical parts in all the figures, of which,—

Fig. 1 is a perspective view of a portion of a wall and flooring having my invention 20 applied thereto; and

Fig. 2 is a top plan view of a portion of the border shown as detached from the parts with which it is assembled in Fig. 1.

In said figure, *a* represents a tile parti- 25 tion wall, and *b* represents the concrete floor on which the partition is erected.

Before the partition wall is built, the novel fastening strips are laid on the floor spaced apart the thickness of the partition 30 wall, and the tile partition set on top of the same between the strips with the necessary mortar *b'*. These strips consist primarily of a center strip *c*, which is preferably com- 35 posed of some wood, but which may be com- posed of some fiber composition, such as sawdust with a suitable binder, or other sim- 40 ilar material. This strip is preferably given the quadrilateral shape in cross section shown in Fig. 1. It is surrounded by a 45 metallic sheathing, which preferably con- sists of the vertical edge portion *d* having the tongues *e* formed on the lower edge there- 50 of, together with the top portion *f*, which preferably has openings or perfora- 55 tions *g* therein, preferably formed by ex- panding that portion of the sheet metal, together with the slanting edge portion *h*, which is connected to the base portion proper *j*, which is preferably imperforate except 60 at its inner edge, where it has the perfora- 65 tions *k* to receive the tongues *e* and where it joins the anchoring portion or strip *l*, which is preferably perforated and corru- 70 gated as shown, the perforations conven- 75 iently being formed by expanding that portion of the metal. When the tile partition

is set, the mortar *b'* beneath the wall *a* enter- 80 ing the perforations *l* serves to anchor the strip securely in place.

After the mortar *b'* has set, the plaster 85 faces *m* are applied to the wall *a*, and after these are applied, the baseboards *n* are nailed against the faces *m* with their bottoms resting on the top of the fastening strip, and the hoods *o* can be nailed onto the 90 tops of the baseboards *n* if desired. The carpet, or other covering, *p*, is then laid on the floor *b* on the padding *t* with its edges extending over the fastening strips and up to, or substantially up to the base- 95 boards *n*, and the carpet can then be secured in place by the tacks *q* nailed through its edges into the strip *c* through the apertures *g* if they are provided. If it is desired to conceal the heads of the tacks *q*, the corner 100 strip *r*, being a quadrant in cross section, can be fitted in place and secured by the nails *s* driven diagonally therethrough and through the perforations *g* into the fibrous strip *c*.

While I have shown and described my invention as embodied in the form which I at present consider best adapted to carry out its purposes, it will be understood that it is capable of modifications, and that I do not desire to be limited in the interpretation of the following claims except as may be necessitated by the state of the prior art.

What I claim as new, and desire to secure by Letters Patent of the United States, is:

1. In a building construction, the combination with a hard plastic floor portion, of a wall rising therefrom, an edge strip se- 90 cured on the floor adjacent the wall, said edge strip being constructed of fibrous ma- 95 terial surrounded by a metallic sheath on all sides, for the purpose described.

2. In a building construction, the combination with a hard plastic floor portion, of a wall rising therefrom, an edge strip inter- 100 posed between it and the wall, said edge strip being constructed of fibrous material surrounded by a metallic sheath, a floor cov- 105 ering extending onto the edge of the strip, and tacks passed through the floor cov- 110 ering, the metallic sheathing, and into the fibrous material.

3. In a building construction, the combination with a hard plastic floor portion, of a hard plastic wall, an edge strip placed ad- 110 jacent the wall and on the plastic floor, said edge strip being constructed of fibrous ma- 115 terial surrounded by a metallic sheath, a

softer plastic layer on the wall and overhanging the edge of the edge strip, and a baseboard resting on the edge strip and nailed thereto.

5. 4. In a building construction, the combination with a hard plastic floor portion, of a hard plastic wall, an edge strip placed against the wall and on the plastic floor, said edge strip being constructed of fibrous material surrounded by a metallic sheath, a softer plastic layer on the wall and overhanging the edge of the edge strip, a baseboard resting on the edge strip and nailed

thereto, a floor covering extending onto the edge of the strip, tacks passed through the floor covering, the metallic sheathing, and into the fibrous material, a corner strip overlying the tacks and engaging the baseboard, and nails passed diagonally through the corner strip, the metal sheathing, and into the fiber.

In witness whereof, I have hereunto set my hand and affixed my seal this 19th day of April, A. D. 1922.

ERIC E. HALL. [L. s.]
